UNITED STATES PATENT OFFICE.

LEMBERT H. MOULTHROP, OF SOUTH NORWALK, CONNECTICUT.

ELECTRIC ATTACHMENT PLUG CAP.

Application filed May 11, 1925. Serial No. 29,357.

This invention relates to electric attachment plug and particularly to the cap portion of separable plugs of this character.

In connecting electrical conductors to contact terminals of attachment plug caps it is customary to knot the conductors within the plug so that the strain of the weight of an electric translating device such as a lamp or electric apparatus, or from a pull on the conductor to separate the plug will come on the knot and not on the connections between the conductors and terminals within the plug and thus breaking the connections. The knotting of the conductors tends to break the insulation of the conductors causing a short circuit and possibly a fire.

It is the object of the invention to overcome the above disadvantages in plug caps of this character by arranging strain receiving means for the electric current conductors within the cap about which the conductors are adapted to be engaged and take any strain upon the conductors and relieve the connections of the conductors with the plug terminals from the strain. Another object of the invention is to provide an electric attachment plug cap of this character of integral structure which is compact and cheap to manufacture.

In the drawing accompanying and forming a part of this specification, I have shown an embodiment of the invention, in which Figure 1 is an elevational view of the attachment plug cap.

Figure 2 is an end view of the plug cap showing an opening through which electrical conductors are passed.

Figure 3 is a sectional view taken on line 3-3 of Figure 5 looking in the direction of the arrows, showing strain receiving means in relation to the opening.

Figure 4 is a sectional view taken on line 4-4 of Figure 5 looking in the direction of the arrows and showing the strain receiving means, and the manner of mounting contact terminals on the plug.

Figure 5 is a view looking at the top of Figure 4.

Figure 6 is a view similar to Figure 5 but showing the electric conductors in connection with contact terminals, and

Figure 7 is a sectional view taken on line 7-7 of Figure 5 looking in the direction of the arrows.

Similar characters of reference designate like parts throughout the different views of the drawing.

The embodiment of the invention illustrated in the drawing comprises a cap 7 of moulded insulating material in the form of a shell of circular shape with an opening 8 at the apex. The interior of the cap is provided with two opposite parallel lugs 9 integral with the wall of the cap and terminating within the cap as at 10 with the opposite sides 11 of the lugs arranged in arcs of a circle to form opposite extended wall portions of the opening 8 to facilitate the passage of electric conductors 12 entered through the opening 8. The gap between the lugs is spanned by a bridge piece 13 which extends transversely of and in spaced relation to the opening 8 and the bottom wall of the bridge piece being of V-shape, as shown at 14, the opening 8 leading into the cap at opposite sides of said bridge piece as clearly shown in Figure 3. A lug 19 is arranged midway between the ends of the bridge piece to extend transversely and outward therefrom.

The ends of the lugs 9 are in the nature of seats for mounting contact terminals shown as blades 15 extending parallel to each other and the axis of the cap. Each of said contact blades has a laterally bent end 16 for engagement with the ends of the lugs 9. These contact terminals are mounted upon the cap by means of bushings 17 (Figure 7) moulded in the material of the cap lugs 9 with a portion projecting beyond the end of the lugs. To attach the contact blades 15 to the cap the projected ends of the bushings are inserted in perforations in portions extending laterally and oppositely from the blade extension 16 and the bushing ends crimped or riveted over said blade extension, as shown at 18 in Figure 7.

In connecting the conductors 12 to the contact terminals 15 the ends of the conductors are passed through the opening 8, one being directed to each side of the bridge piece, this being facilitated by arranging the bottom wall 14 of V-shape. The conductors are then engaged over the bridge piece, to engage between the bridge lug 19 and contact blades 15, and then bared ends are bent around the contact blades, as at 20,

and guided by a ledge 21 extending beyond the contact carrying lugs 9 from one side thereof to be engaged about and below heads of binding screws 22 threaded into the blade 5 extensions 16 intermediate the connection thereof with the bushings 17 to engage in recesses 24 moulded in the cap lugs 9, Figures 4 and 7.

By the arrangement described and illustrated of engaging the conductors about the contact terminals any strain by a pull exerted on the conductors will be transmitted to and taken up by the bridge piece and the connections of the conductors relieved of all 15 of such strain, with the result there will be no possibility of loosening the conductors from the binding screws 22 and consequent breaking of the electric circuit. Furthermore there is no possibility of breaking the 20 conductors' insulation and consequent short circuit.

The conductor and contact connections may be enclosed in the cap by a disk 23 releasably engaged in the end of the cap to 25 rest upon the parts 19, 21 and having openings for the passage of the contact blades 15.

Having thus described my invention, I claim:

1. In an electric attachment plug, a cap 30 having an opening, lugs, within the cap at opposite sides of the opening arranged for the mounting of contact terminals thereon, a bridge piece integral with said lugs and within the contour of the cap extending transversely of the opening and between the 35 lugs and having a lug extending outwardly centrally between the ends thereof forming channels in the bridge piece between the lugs, said bridge piece being adapted to take up 40 the strain of a pull on electric conductors passed through the opening to opposite sides and over the bridge piece and about contact terminals mounted on the lugs to which the conductors are connected.

2. In an electric attachment plug, a cap 45 having a central opening at one end, parallel lugs at opposite sides of the opening integral with and extending inwardly from the wall of the cap arranged for the mounting of 50 contact terminals on the end thereof, a bridge piece integral with and within the contour of the cap extending transversely of the opening and between the lugs and having an outwardly extended lug intermediate 55 the ends thereof, each of the parallel lugs having one side arranged to co-operate with the bridge piece to form passages for electric conductors communicating with the opening into the end of the cap, and said bridge piece 60 adapted to take up the strain of a pull on the electric conductors passed through the opening to the passages at opposite sides and over the bridge at opposite sides of the intermediate lug and connected to contact 65 terminals mounted on the lugs.

3. In an electric attachment plug, a cap having an opening entering centrally into one end, a bridge piece integral with and within the contour of the cap extending transversely of the opening and said opening communicating with the space at opposite sides of said bridge within the cap and the contour of the bridge facing toward the opening being of V shape in cross section for facilitating the separating and guiding of 70 electric conductors passed through the opening to opposite sides of the bridge piece, and the opposite face of the bridge arranged with transverse grooves for engagement and separating of the conductors passed over the 75 bridge.

4. In an electric attachment plug, a cap of molded insulating material having an opening entering therein axially at one end, oppositely disposed lugs within the cap having mounting members for contact terminals moulded therein and having an integral portion extending between said lugs to bridge the opening arranged to form channels between the contact mounting members, said bridge portion being adapted for the engagement thereover of electric conductors passed through the cap opening to opposite sides of the bridge and connected to contact 90 terminals secured to the cap by the contact 95 mountings, and said bridge being adapted to take up the strain of any pull on the conductors to relieve the connections of the conductors with the terminals of any such strains.

5. In an electric attachment plug, a substantially hemispherical cap of molded insulating material having an integral transverse bridge piece therein, contact terminal mounting members molded in the material of the cap at opposite ends of the bridge, contact terminals mounted thereon to extend outwardly from the cap arranged for the connection of electric conductors, and an opening leading into the cap to opposite sides of the bridge piece for the passage of electric conductors to be engaged over the bridge piece and about the contacts and connected to the latter whereby said bridge piece is adapted to take up the strain of any 115 pull upon the conductors.

6. In an electric connection plug, a cap of moulded insulating material arranged with a transverse integral bridge piece having a lug extending outward and transversely intermediate the ends thereof, contact blades mounted on the outer side of the bridge piece spaced from and extending parallel to and beyond the bridge lug, and an opening leading into the cap to opposite sides of the 120 bridge piece for the passage of electric conductors to be engaged over the bridge piece from opposite sides thereof in interposed relation to the bridge lug and contact blades 125 and passed around the contacts for connec- 130

tion therewith at the outer sides whereby strains on the conductors are adapted to be taken up by the bridge piece.

7. A cap member for separable electric connection plugs embodying a substantially hemispherical shell of molded insulating material having an integral bridge piece extending transversely of the open end and within the shell arranged with an outwardly

10 extending lug intermediate the ends thereof

and an opening centrally through the crown wall of the shell, and contact terminal mounting members molded into the material of the cap at opposite ends of the bridge piece.

Signed at the city of New York, in the county of New York and State of New York this 1st day of May, 1925.

LEMBERT H. MOULTHROP.
